UNITED STATES PATENT OFFICE.

CLAUDE J. HOLSLAG, OF SOUTH ORANGE, NEW JERSEY.

MASK FOR USE IN ARC-WELDING OR ALLIED WORK.

1,305,364.

Specification of Letters Patent. Patented June 3, 1919.

Application filed October 21, 1918. Serial No. 259,039.

To all whom it may concern:

Be it known that I, CLAUDE J. HOLSLAG, a citizen of the United States, residing at South Orange, in the county of Essex and 5 State of New Jersey, have invented certain new and useful Improvements in Masks for Use in Arc-Welding or Allied Work, of which the following is a specification.

In the operation of arc welding whether 10 by a gas flame, such as oxy-acetylene, or by the electric arc, using carbon or metallic electrodes, as well as in the operation of cutting or reducing by the above methods or others in which an arc flame is used, it is 15 necessary that not only the eyes of the operator be protected from the intensive light of the arc but the exposed portions of the operator's face and neck must be protected so as to prevent dangerous burning from 20 the arc.

It is the object of my invention to provide a mask which gives the necessary protection from the arc rays under different working conditions but also to provide a 25 mask which is a mechanical protection as it very often happens, where welding and riveting are both going on around a large industrial project, that rivets or other substances are apt to fall and strike some welding operator on the head with serious results.

Another object of my invention is to provide a mask that allows the operator the use of both hands for operating a welding, cutting or reducing apparatus.

30 Other and further objects will be apparent to one skilled in the art after a study of the specification taken in connection with the drawing, wherein Figure 1 illustrates a side elevation of the mask placed in position 40 over the operator's head.

Fig. 2 shows the mask tilted up for the purpose of direct observation.

Fig. 3 is a front view of the mask shown in Fig. 1.

45 Fig. 4 is a sectional view, on the line 4—4 of Fig. 3.

Referring now to the details, wherein like numbers refer to corresponding parts in the various views, the mask has a top portion 1 which, in my preferred form shown, is rounded to fit the operator's head 2 on which a cap 3 is shown in reversed position, which is the usual method of wearing a cap adopted by welding operators. The top portion 1 extends or merges into side portions 4 and 5 whose lower sections 6 and 7 preferably

taper downward and inward to a point closely adjacent the shoulders of the wearer thus covering the throat and neck. The front portion 8 carries in a holder 9, which 60 is fastened to portion 8 as by screws 10 and nuts 11, a series of shields 12, 13 and 14 of different colored glass through which the operator may observe the weld or the work that is being performed. These glass shields 65 may consist of any combination of colors, such as one white, one green and one blue, or one green and two ruby. I do not wish to limit myself to any particular combination of colors.

70 The receptacle 9, carrying the shields, is mounted in the portion 8 so that the center of the shields is somewhere near in line with the operator's eye. The side portions 4 and 5 are bridged by a member 15 which is 75 preferably integral with the top portion 1 thereby bracing the side portions 4 and 5 to prevent their spreading. The bridge 15 also passes downward far enough so as to engage the back of the operator's head, as 80 16, so as to prevent the mask from tipping forward off of the operator's head. It will be observed that this construction leaves an opening for the insertion of the operator's head between the side portions 85 18 and the bridge. The lower part of the front 18 bends inward and downward as at 17, terminating in a relatively narrow and stiff part 18 which serves as a handle for the mask. In some cases I prefer to fasten to 90 the lower portion 18 a flap 19 of flexible material, such as leather which flap serves the function of further protecting the throat and chest of the operator when the operator is lying on his back welding or doing what 95 is known as overhead welding or cutting. For ordinary welding purposes the flap 19 is not required.

An important feature of my mask is that when the operator requires to have direct 100 observation for the purpose of climbing a ladder or moving around or fitting a new electrode to his holder, he seizes the mask at the handle part 18 tilting it back on his head, as shown in Fig. 2. This allows the 105 operator to look between the side portions 6 and 7 between the points 20 and 21, the flap 19 when used being thrown back over the portion 17. It will be seen from Fig. 2 that the sides of the face and eyes of the operator are still protected from arc rays coming from another machine working in close

proximity so that the portions 6 and 7 act as blinders to cut off such interfering rays. It will be apparent that heat rays as well as light rays are cut off by this construction.

- 5 Another important object is obtained in the construction of my mask, as shown in Fig. 2, and that is that when the operator tilts the mask backward for direct observation purposes the inner shield 12 is wiped 10 or rubbed over the head or head-gear, such as a cap 3, of the operator thus wiping off the moisture that accumulates on the inner shield from the operator's breath.

In order to give the operator ventilation,

- 15 I place some ventilating means in the top portion 1, such as a hole 22 over which I fasten a piece of wire gauze 23 which will prevent small objects from falling through the hole 22.

- 20 In my preferred form of mask herein described, it will be noted that the different portions are shown one a continuation of the other, forming an integral structure, and I have obtained such a construction by making 25 the mask of "papier mâché" which, after the molding process, is treated with preferably black insulating and refractory paint. This construction produces a mask which is very light and stiff since the exposed edges are 30 preferably reinforced with ratan. A mask constructed as herein described while being extremely light, possesses a great deal of strength and on account of the curvatures shown affords great protection to the operator from falling objects. A mask so constructed is well balanced on the operator's head either in the normal working position, shown in Fig. 1, or in the direct observation position, shown in Fig. 2, so that the operator 35 has full use of both hands for application to the work before him.

While I have shown a preferred shape of mask, I do not wish to be limited to the exact contour or construction except as limited by 40 the appended claims.

Having thus ascertained the nature of my invention and in what manner the same is to be performed, I declare that what I claim is:

- 45 1. A mask for use in arc welding or allied work having, top, front and side portions with a bridge across the back joining the side portions, said top portion extending from one side portion to the other completely covering the opening therebetween and forming a rigid protecting cover over the user's head, but leaving for the user's head an opening extending below said bridge between the side portions and means carried 50 by the front portion through which the arc may be observed without injury to the user.
2. A mask for use in arc welding or allied work having top, front and side portions, said top portion being rounded over and 55 adapted to rest on the head of the wearer

and merging into said side portions which taper downwardly and preferably inwardly to a point near the shoulders to protect the neck of the wearer, said front portion extending downward and preferably inwardly 70 over the throat of the wearer and carrying means through which the arc may be observed without injury to the observer, and a bridge portion joining said side portions and preferably the top portion with them, 75 said bridge portion adapted to pass behind the head of the wearer to assist in holding the mask thereon.

3. A mask for use in arc welding or allied work having top, front and side portions, 80 said top portion having ventilating means therein and being formed so as to rest on the head of the user and merging into said side portions which taper downwardly near the shoulders to protect the neck of the user, 85 said front portion extending downwardly over the throat of the user and carrying means through which the arc may be observed without injury to the observer and a bridge portion joining said top and side 90 portions but leaving an opening extending below said bridge between the side portions, said bridge serving also to engage the back of the user's head to assist in holding the mask thereon.

4. A mask for use in arc welding or allied work according to claim 2, in which the lower side and front portions terminate in a relatively narrow and stiff part for handling the mask as well as giving increased protection to the wearer at the throat.

5. A mask for use in arc welding or allied work according to claim 4, in which a flexible flap of suitable material is attached to the lower stiff part of the mask for the purpose 105 described.

6. A mask for use in arc welding or allied work having top, front and side portions with a bridge across the back joining the side portions, but leaving an opening extending below said bridge between the side portions and means carried by the front portion through which the arc may be observed without injury to the observer, said mask having two operative positions, one in which the top portion rests on the head of the user and the arc observation means is in front of the user's eyes; and second, a tilted position in which the front portion rests on the head of the user whereby the lower part of said opening is shifted to a point where the user may have direct observation.

7. A mask for use in arc welding or allied work having top, front and side portions with a bridge across the back joining the 125 side portions, but leaving an opening extending below said bridge between the side portions and means carried by the front portion through which the arc may be observed without injury to the observer, said 130

mask having two operative positions, one in which the top portion rests on the head of the user and the arc observation means is in front of the user's eyes; and second, a tilted 5 position in which said observation means in the front portion is brought in contact with the head or head-dress of the user whereby said observation means is wiped off and the lower part of said opening is shifted to a 10 point where the user may have direct observation.

8. A mask for use in arc welding or allied work having top, front and side portions with a bridge portion joining said top and side portions, said top portion to fit over the 15 head of the user, said front portion carrying shields through which the arc may be observed without injury to the observer, all of said mentioned portions being shaped into a one piece rigid structure as described. 20

In witness whereof, I affix my signature.
CLAUDE J. HOLSLAG.

It is hereby certified that in Letters Patent No. 1,305,364, granted June 3, 1919, upon the application of Claude J. Hohlag, of South Orange, New Jersey, for an improvement in "Masks for Use in Arc-Welding or Allied Work," errors appear in the printed specification requiring correction as follows: Page 2, line 53, claim 1, after the word "portions" insert the words *but leaving for the user's head an opening extending below said bridge between the side portions*; same page and claim, line 57, commencing with the word "but" strike out all to and including the word "portions," line 59; and that the said Letters Patent should be read with these corrections therein that the same may conform to the record of the case in the Patent Office.

Signed and sealed this 29th day of July, A. D., 1919.

[ANAL.]
